WALL CABINET AND CLOCK

Joseph A. Hoegger, North Bergen, N. J.

Application November 16, 1932, Serial No. 642,836

7 Claims. (Cl. 312—112)

My invention relates to the combination of a clock and door, and more particularly to the combination of a clock with a wall cabinet. I realize that clocks have previously been used with mirrored surfaces. However, in such cases, the mirror has been a stationary structure and the clock was either inserted in a hole cut in the mirror, or else fixed against the back of the mirror, the mirrored surface over the face of the clock having been removed.

My invention consists in obtaining the effect of a clock permanently fixed in a surface, which surface, however, is hingedly connected and which is adapted to swing away from the clock. I have specifically shown my invention in connection with a wall cabinet having a door with a mirrored surface. When the door is closed, the clock attached to the cabinet has the appearance of being set in the mirrored surface of the door. When the door of the cabinet, however, is swung open, the clock remains within the cabinet and is enclosed by a protecting cover therein.

Referring more particularly to the drawing in which like reference characters denote like parts: Figure 1 is a front elevation of my invention with the door closed and the clock appearing in its face;

Figure 2 is a sectional detail taken at 2—2 of Figure 1;

Figure 3 is a broken sectional detail taken at 3—3 of Figure 2; and

Figure 4 is a broken perspective view of the clock within the cabinet.

The structure I have shown consists primarily of the swinging surface or door 10, the clock 11, and the support for the clock, as illustrated, the cabinet 12. The door has preferably a mirrored surface 10' and is connected by means of hinges to the cabinet 12 so that it can be conveniently swung to an open or closed position. For the purposes of beauty, I have shown the mirrored door of such a size that when closed it completely covers the cabinet opening and gives the impression of a wall mirror. The cabinet is preferably set in a wall recess, the wall being indicated by reference character 13. It is possible, of course, to use my invention in connection with a door not necessarily attached to a recessed cabinet.

The door 10 is fitted with a frame 14. A backing 15 which may be of fibre board is used to give added support to the mirrored surface 10'. I have also shown a metal backing 16 to give a finished appearance to the door when open. The door has in it an opening 17 of substantially the same size as the face of the clock 11. The clock

has a face 18 projecting into the plane of the door when it is closed. The clock is enclosed and supported within the cabinet by means of the metal box 19. This clock box 19 I have shown as supported within the cabinet by means of the upper turned flanges 20 which operate in the slots 21 attached to the cabinet. The box 19 does not have a back where it bears against the back of the cabinet 12' and can be pulled out from the cabinet, the flanges 20 sliding in the slots 21.

In the modification illustrated, I have shown an electric clock which has several advantages from the standpoint of convenience although it is not necessary to use such a type of clock in carrying out my invention. I have shown an electric connection 22 extending from the clock mechanism housing 19' to an electrical plug and slot connection 23. This plug is connected to a second plug and slot connection 24 from which an electrical conduit 25 extends through a hole in the upper part of the cabinet 26 to any convenient source of electrical supply. The electrical plugs and connections 23 and 24 preferably rest on an insulation plate 27 and are enclosed in a metal box 28 which may be screwed to the back of the cabinet by the screws 28'. The clock housing 19' at its extending surface has a glass face 29 which is held in position against the turned edge of the projecting rim 18 by means of an internal rim 30. The hands 31 of the clock move within the space thus formed.

It is clearly seen from Figure 2 that when the door is closed, the face of the clock 19' projects into and fits snugly within an open portion of the door enclosed by the rim 17. If a mirrored surface for the door is used, the mirrored portion is removed over the face of the clock so that when the door is closed, the clock is seen through the door as shown in Figure 1. The turned-in edge 17' of the flanged rib 17 lies against the back of the mirror and forms a frame for the clock. The mirror may be grooved slightly on its inner side where the edge 17' bears against it in order that a finished appearance may be given to this framing effect. The projecting face of the clock is adapted to fit as snugly as possible within the rim 17 and yet still permit the swinging of the door against and away from the clock and cabinet. The arc of the swing of the door will be so small that a very snug fit can be obtained which gives the appearance that the clock is actually set in the glass mirror.

The clock is completely enclosed and protected

by the box 19 as it always remains in position within the cabinet. The clock, however, may be easily removed for inspection, setting, or repair, by merely pulling outwardly the box 19 which 5 slides through the grooves 21 and, if electrically operated, disconnecting the plug connection 23.

The cabinet may be inserted in a wall recess and an electrical connection inserted through hole 26 and plugged into the connection 24 for 10 operating the clock. The cabinet may, of course, be fitted with shelves, lights or other equipment not shown.

While I have shown a particularly convenient and useful method for combining a clock with a 15 swinging or movable surface, I do not wish to be limited to the specific structure which I have shown as it will be apparent to those skilled in the art that there are other modifications which will be within the purview of my invention.

20 What I claim is:

1. The combination comprising a cabinet, a door for said cabinet, said door having a mirror face and a backing, a clock within said cabinet and attached thereto, the backing of said door having a recessed portion adapted to enclose the face of said clock when said door is in closed position, said mirror face having no mirrored surface over the face of said clock.

2. The combination comprising a cabinet, a 30 mirrored door for said cabinet, said mirrored door having a mirror-supporting back, a clock attached to said cabinet having a face projecting beyond the plane of the cabinet opening, said mirror-supporting back having a recessed portion adapted to enclose the face of said clock when said door is in closed position, a flanged rim defining said recessed portion in said door and lying against the back of said mirrored surface, said mirror being free from said mirrored surface at the portion thereof lying over the face of said clock.

3. The combination comprising a cabinet, a 45 mirror door for said cabinet, a supporting back for said mirror door, a clock within said cabinet having a face projecting beyond the plane of the opening of said cabinet, a box within said cabinet supporting and enclosing said clock, said door having a recessed portion adapted to enclose the projecting face of said clock when the door is in closed position, the face of said clock being adapted to lie in close relationship with said mirror, the mirrored surface being removed from that portion of the mirror lying over the face of the clock.

55 4. The combination comprising a cabinet adapted to be recessed in a wall, a mirrored door

hingedly connected to said cabinet and adapted to completely cover said cabinet when in closed position, said mirrored door having a mirror-supporting back, a clock within said cabinet having a face projecting beyond the plane of the rear surface of the door when in closed position, 80 a box enclosing said clock and supporting the same, said box being detachably connected to said cabinet, said mirror-supporting back having a recessed portion adapted to enclose the projecting face of said clock, a rim defining said recess in said door backing and adapted to snugly enclose said projecting clock face, said mirror being left clear and transparent at the portion thereof covering the face of the clock.

5. The combination comprising a cabinet, a mirrored door for said cabinet, a supporting back for said mirrored door, an electric clock within said cabinet having a face projecting beyond the plane of the cabinet opening, electrical connections attached to said cabinet, conduits connecting said clock and connections and said connections with a source of electrical supply, a box within said cabinet supporting and enclosing said clock and also enclosing said electrical connections, said door having a recessed portion adapted to enclose the projecting face of said clock when the door is in closed position, the face of said clock being adapted to lie in close relationship with said mirror, the mirrored surface being removed from that portion of the mirror lying over the face of the clock.

6. The combination comprising a swinging door attached to a supporting means, a mirror for said door, a clock attached to said supporting means and positioned behind said door when in closed position, said clock having a face projecting into the back of said door and adapted to lie in close relationship with said mirror when said door is in closed position, said door having a recess adapted to receive said clock face, the mirrored surface being removed from said mirror at that portion covering the clock face.

7. The combination comprising a supporting means, a door hingedly attached to said means, a clock attached to said means and lying behind said door when in closed position, said door comprising a mirror, said clock being positioned to lie in close relationship with said mirror when in closed position, the mirrored surface on said mirror being removed over the face of said clock, a backing for said mirror having a recess adapted to receive the clock face, said clock having a face projecting beyond the plane of the rear surface of the door when in closed position.
